CAKE FROSTING FORMING MAT

Adolph Benz, 609 S. Western Ave., Peoria, Ill.

Filed July 19, 1965, Ser. No. 86,204

Term of patent 14 years

(Cl. D44—29)

FIG. 1 is a top plan view of a cake frosting forming mat showing my new design;

FIG. 2 is a front edge elevational view.

FIG. 3 is a bottom plan view, and

FIG. 4 is a side elevational view.

I claim:

The ornamental design for a cake frosting forming mat, substantially as shown.
